BEAM AMPLIFIER TUBE

Norman Z. Ballantyne, Lewiston, Idaho

Application February 15, 1950, Serial No. 144,223

10 Claims. (Cl. 313—72)

1

This invention relates to improvements in electron tubes of the beam amplifier type.

It is an object of the invention to provide a tube of the beam amplifier type which will enable direct coupling from the anode of a preceding tube to its controlling element and thus provide a direct path for the signal voltage developed across a plate load common to both the controlling element and the anode, without the use of cumbersome biasing and divider circuits as has heretofore been necessary.

A further object is to provide a tube which can be easily used as a direct current amplifier. Heretofore, in tubes the control element had to be biased below or at the cathode potential requiring cumbersome circuits used without coupling. With the tube herein presented such circuits are not necessary as one control element is always maintained positive with regard to the cathode, and increasing its positive merely increases the electrostatic lens action; and swinging it negative decreases the lens action.

A further object is to provide a tube by means of which phase inversion is accomplished. In the tube one element under control will alternately increase and decrease the current flowing to each of two electrodes which have equal, opposite changes in current. Phase inversion can be accomplished by the tube itself with the opposite phase removed from the equal plate loads of a target anode and target plate.

A further object is to provide a tube with a much more linear curve than possible with tubes heretofore produced; and to provide a tube with high internal resistance. Also the tube will draw a constant current from a power supply; and external circuit parts are eliminated without sacrifice to fidelity of response.

A further object is to provide a tube in which microphonic troubles are, to a large extent, eliminated; and to provide a tube which does not decelerate the electrons as they leave the cathode wall. In the tube herein presented the electron density per unit area of the beam cross section remains constant or becomes greater.

A further object is to provide a tube which can be constructed of vertically aligned parts; and which has the ability to be used as a push-pull amplifier with one envelope.

A further object is to provide a tube in which there is no phase shift between input and output. Also in the tube herein presented harmonic and frequency distortion is reduced.

These and other objects are attained by the novel construction and arrangement of parts herein described and illustrated by the accom-

panying drawings, forming a part hereof and in which:

Figure 1 is a plan view of a beam amplifier tube embodying the invention.

Fig. 2 is a plan view of a modified form of the tube.

Fig. 3 is a plan view of another modified form of the tube.

Fig. 4 is a plan view of a further modified form of the tube.

The tubes herein presented are of the same general type as the tube described in detail in my application for patent, Serial No. 99,499, filed June 16, 1949, Patent No. 2,569,971; issued October 2, 1951. Referring to the drawing, in Fig. 1 is shown a form of tube having an envelope 1, in which is mounted a cathode 2 having a coated surface of an oxide 3 which emits electrons when properly heated.

The emitted electrons are repelled by a charge at or near cathode potential applied to a focusing structure 4, comprising substantially, a cylinder with an opening 5 for the passage of electrons towards accelerating structure including a plate 6 located to one side as shown in Fig. 1. The effective width of the opening 5 can be controlled by varying the voltage to the focusing structure. Beyond the opening 5, the plate 6, which is positively charged, causes electrons emitted from the cathode 2 to accelerate through the opening 5.

As the electrons pass through the opening 5 they have a high linear velocity, and the various electron paths approach collimation in a vertical plane, considering that the cathode is vertically aligned.

In this manner a beam is set up. The focusing structure allows the electrons to move only through the opening 5, causing the formation of a beam in the horizontal plane and the accelerating structure causes the electrons to approach collimation in a vertical plane, with resultant equal electron density along the vertical axis.

Electrons moving outward from the opening 5 are attracted by a positive deflection plate 7, which is curved inwardly towards the electron beam. That is, the center of curvature of the positive deflection plate is on the same side of the plate as the electron beam. A negative deflection plate 8 is maintained at or below cathode potential and consequently it will not be bombarded by electrons moving outwardly from the opening 5. Since the electrons cannot bombard the plate 8 they begin to lose some of the applied linear velocity. The electrons are 55 deflected from plate 8 and attracted towards

3 plate 7, which is in line with a target plate 9 having substantially the same curvature in the same direction as plate 7. Plate 9 also has applied thereto a positive potential and the electrons acquire a high angular velocity, which together with the effect of the negative deflection plate 8 and the positive potential applied to a target anode 10 cause the curved paths of the electrons to converge and focus on the separator plate. The path of the electron beam can obviously be controlled by varying the potentials on the various plates 7, 8 and 9.

It will be seen that the electrostatic field shift is but a small part of the control factor. For that reason this tube is not to be construed as simply an electrostatic deflecting tube. The electrostatic shift is secondary to the lens warp which occurs when deflection plate potential is applied and shifted. A separator plate 11 is operated at a lower potential than the target anode insofar as static potential is concerned and will maintain some potential difference even at maximum swings in the voltage applied to either the target anode or target plate. Since it is operated at a lower potential in a field of much higher potential the total amount of beam current bombarding the separator plate at no time is very large. This current is normally zero.

When the point of focus is placed upon the separator plate the beam will divide on either side of the plate and be flowing equally to the target anode and to the target plate.

In Fig. 1 is shown the circuit for a zero resistance audio amplifier.

In this case the currents of the positive deflecting plate and target plate are combined by tying the two together. The resultant negative resistance for the combined elements is quite large and can be balanced with an equal but opposite positive resistance on the target anode.

With the target anode and target plate currents equal and opposite and with the target plate and target anode resistances equal in magnitude but opposite in polarity the resultant gain, with a coupling co-efficient of one or closely approaching one, is extremely large since the tubes resistance is effectively cancelled out.

In Fig. 2 is shown a modified form of the tube in which the positive deflecting plate is omitted. In Fig. 1, in the voltage and paraphase amplifier the potential deflecting plate and the target plate are separately connected to the circuit. The tube shown in Fig. 2 is similar to the tube of Fig. 1, and can be used on both the voltage and paraphase amplifier with slight changes in the positions of the elements between the two. In the tubes the active cathode is maintained relatively small and arranged so that the beam current will be low without sacrificing electron density. As a voltage amplifier, the target plate resistance can be raised to infinite values if desired, either by slightly changing the position of the potential deflecting plate 7, or by slight changes in the voltage applied. The resistance of target anode 10 is reduced to low values by such action.

In Fig. 2 is shown the circuit for a single end A. F. voltage amplifier.

This circuit employs a model of the tube having a high target plate resistance but with a correspondingly low target anode resistance resulting from this small change in structure. Also the total current is restricted, if desired, to very low values.

The target plate resistance being large but with the change in target anode and target plate

4 currents remaining equal due to the control of the negative deflecting plate, the amplification of this tube will be very large with an extremely low distortion. Since the characteristic curve of transconductance is straight over a much larger portion of the tube's curve and since the normal driving or zero signal point is exactly halfway along the curve with equal straightline portions on either side, this tube can be driven, as can all tubes of this type, much harder without distortion than can the ordinary tube.

In Fig. 3, a modified form of tube is shown in which the elements are similar to the tube of Fig. 1 with the exception that the separator plate 11 of Fig. 1 is omitted and the target plate 18 and the target anode 20 are substantially semi-cylindrical in shape opening towards the cathode, forming Faraday boxes. This type of tube can be used for power amplification and can be made with low plate resistors.

In Fig. 3 is shown the circuit for a push-pull audio power amplifier.

The tube in this case has a high total current (produced by the increased cathode length) and a low plate resistance (produced by the Faraday box construction of the target plate and target anode).

With an audio input signal on the negative deflecting plate producing signal voltage changes which will change the relative negative deflecting plate to cathode voltage the electron beam will be alternately swung from the target anode to the target plate and back as the signal voltage varies. Due to the low internal resistance in the tube the response of this circuit to mechanical inertia in the speaker or to changing impedance load in the secondary will be very good, approaching the best triode operational performance. With this low resistance will also be the advantage of a much higher total gain than is present in a triode amplifier.

In Fig. 4 is shown a tube designed for power amplifying purposes and consists of two tubes such as the tube shown in Fig. 3 operating in one envelope to provide a twin section amplifier for very high currents. This tube can be used with all the elements of the tube section to the left operating in parallel with the same elements on the right as shown by the dotted lines. In this case very high currents with maximum use of the cathode heating power would be produced. This tube can also be so connected as to be used as a two stage amplifier in much the same way as the present day twin triode is operated. The cathode is increased in length as are all of the tube elements, to provide a much higher beam current without vastly increasing the electron density.

In Fig. 4 is shown the circuit for a cascade audio power amplifier.

The use of a double section tube increases the efficiency of the tube's operation by liberating electrons from both sides of the cathode and thus for the same, or nearly the same, cathode heating power, double the beam current is produced. One of the deficiencies of this type of tube is the relatively low beam current developed from the cathode heating power. By reducing the active cathode area and by other means single section cathode efficiency may be increased but it cannot approach the efficiency of the double element section.

In the cascade audio frequency power amplifier the two sections of the beam are used in cascade in the same manner as individual sections would

be used. In the cascade R. F. power amplifier the same basic circuit is used. In the parallel push-pull A. F. power amplifier the elements are simply connected in parallel to develop a larger plate current than could be developed in the single section. The output is taken in push-pull while the input is driving the individual sections in parallel.

From the above description it will be seen that there has been provided a beam amplifier tube of simple structure, easy to manufacture and control, and which is arranged to provide a beam of constant intensity, that is, the current drawn from the cathode is, or nearly is, a constant, which is not true of tubes heretofore provided. The description is to be considered as illustrative and not limitative of the invention of which modifications can be made without departing from the spirit and scope of the invention as set forth in the appended claims.

I claim:

1. An electron discharge device comprising an envelope, an electron emitting cathode mounted in said envelope, a beam focusing means partially surrounding the electron emitting cathode, separate accelerating electrodes disposed to either side of the opening in the beam focusing means, a curved control electrode disposed with its extreme end obstructing the electron beam path as produced by said beam focusing means and said accelerating means, a target plate, and a target anode disposed to the end of said control electrode and near the end of said accelerating electrode opposite the control electrode with said accelerating electrode and said electron beam converging toward one another.

2. An electron discharge device comprising a cathode, beam forming means with an opening, for the passage of electrons formed into a beam, separate accelerating means disposed to either side of said opening with one of said accelerating means curved in its outer extremity to intercept electrons in said beam, a control electrode disposed parallel to said beam near said accelerating means with said control electrode curved into the path of said beam at the outer extremity of said control electrode, and a target anode positioned between the outer extremities of said curved accelerating electrode and said control electrode.

3. An electron discharge device comprising a cathode, a beam forming means partially surrounding said cathode and directing electrons into beam paths, accelerating means disposed beyond said beam forming means and further disposed with such relation to said cathode and said beam forming means as to prevent electrons in said beam paths striking said accelerating means, a curved control electrode so disposed as to curve into said beam paths, a curved target anode disposed near the end of said control electrode, and a curved target plate disposed near the side of said target anode with the center of radius of the curves, said target plate and said target anode disposed towards the cathode.

4. An electron discharge device of the amplifying type comprising a cathode, beam forming members disposed at either side of said cathode, accelerating members disposed beyond said beam forming members from said cathode, curved deflection control plates with one positioned on either side of said cathode beyond said accelerating members and curved into the electron beam paths as projected from said accelerating members, a curved target anode positioned near the

extreme end of said curved control plate on either side of said cathode, and a curved target plate positioned on either side of said cathode with the centers of radius of said curve in said target anode and said target plate disposed towards said cathode.

5. An electron discharge device of the beam amplifying type comprising a cathode, beam forming means partially surrounding said cathode, accelerating means disposed to either side of the opening in said beam forming means with one accelerating member disposed into a curve along the path of said electron beam with the center of radius of said curve disposed towards said electron beam, a curved control electrode disposed to the other side of said electron beam with the center of radius of said curve disposed towards said electron beam, a curved target plate disposed near the end of said curved control electrode with the center of radius of said curve disposed towards the cathode, a substantially circular target anode disposed near the end of said control electrode, and a flat separator plate disposed between said target anode and said target plate.

6. An electron discharge device comprising a cathode, beam forming means partially surrounding said cathode, accelerating means disposed to either side of the opening in said beam forming means and further disposed as to be shielded from direct electron bombardment from said cathode, a curved control electrode disposed near one accelerating member and further disposed to curve into the path of said electron beam as projected by said accelerating means, a target anode disposed near the end of said control electrode, and a target plate disposed between said target anode and said accelerating means opposite said control electrode.

7. An electron discharge device comprising a cathode, a beam forming means partially surrounding said cathode, a flat accelerating member on one side of the opening in said beam forming means with the major dimension of said accelerating member substantially perpendicular to the electron beam formed by said beam forming means with said accelerating member further disposed to be shielded by said beam forming means from direct bombardment from said cathode, an accelerating member disposed to the other side of the opening in said beam forming means and shielded by said beam forming means from direct bombardment from said electron beam with said accelerating means further disposed to be farthest away from the electron beam path at the center of width of said accelerating means, a curved control electrode disposed beyond said flat accelerating member from said cathode with said control electrode curving into said electron beam as the distance from said cathode is increased, and a target anode disposed near the extreme end of said control electrode as seen from said cathode.

8. The structure set forth in claim 7 in which the target anode is a curved member with the center of radius of said curve disposed toward said cathode.

9. The structure set forth in claim 7 in which the target anode is a substantially circular rod and a separator plate is disposed to the side of said target anode opposite from the side of said target anode disposed toward said control electrode.

10. An electron discharge device comprising a cathode, beam forming means partially sur-

rounding said cathode, a first accelerating member disposed to one side of the opening in said beam forming means and further disposed to be shielded by said beam forming means from direct bombardment from said cathode, a second accelerating member disposed to the opposite side of said opening in said beam forming means and further disposed to be shielded by said beam forming means from direct bombardment from said cathode with said second accelerating member further disposed to be farthest from said electron beam at the center of width of said accelerating member, a curved control electrode disposed beyond said first accelerating member as seen from said cathode and further disposed to curve into the path of said electron beam as said beam progresses away from said cathode, a target anode formed of a curved member with the center of radius of said curve disposed towards said cathode with said target anode disposed near the end of said control electrode, and a target plate formed of a substantially curved member with the center of radius of said curve disposed towards said cathode with said target plate further disposed be-

tween said target anode and said second accelerating means.
